UNITED STATES PATENT OFFICE

GORDON R. STREICH, OF BUFFALO, NEW YORK

CURTAIN AND VALANCE OR LAMBREQUIN SUPPORT

Application filed August 27, 1928. Serial No. 302,337.

This invention relates to supports for curtains or other draperies such as valances or lambrequins employed in the decoration of doors, windows and the like, and in hanging decorative curtains from the ceilings of halls or display rooms, or from walls above windows.

Heretofore it has been customary in decorating large windows or in hanging relatively heavy draperies or valances to provide a wooden framework having a central portion disposed in a horizontal plane and two depending leg portions at the ends thereof so as to form a substantially shelf-like structure upon which the draperies were tacked or otherwise secured. Considerable difficulty and expense have been encountered in this method for the reason that such construction is not only of a permanent nature that is not readily removed without the disfigurement of the walls or woodwork to which it is secured, but in addition considerable waste is encountered in sawing the material to the shape desired, particularly in the case of doors or windows with arched or irregularly shaped frames. Moreover, if it is necessary to secure a structure of this type to a ceiling, there is danger of disfiguring the paper or other surface by the inherent rugged nature of its attachment thereto.

One of the objects of the present invention is to avoid the difficulties hereinabove mentioned by providing a curtain or valance support constructed of a flat metallic strip which may be bent to conform to the shape of a door or window frame and which is provided with a row of apertures along each edge thereof, the apertures of one row being adapted to receive nails or screws for convenient attachment to the frame and the apertures of the other row being adapted to receive a series of hooks for removably suspending a drape from the support.

Another object of the invention is to provide a support of the character described which may be manufactured in certain prescribed lengths and, thereafter, cut to the desired length to order or at the time of hanging the draperies.

Still another object of the invention is to

provide a support of the type described that may be bent longitudinally in order to permit of its attachment to the wall or ceiling when the door or window is not provided with a frame or when they extend entirely to the ceiling and also when it is desired to extend the draperies over the wall sufficiently to give the effect of a larger door or window.

A further object of the invention is to provide a support of the character described which will maintain the draperies against displacement in the desired gathered position.

Other objects will appear from the following specification and appended claims.

In the accompanying drawings:

Fig. 1 is a perspective view of a portion of a support constructed in accordance with the invention.

Fig. 2 is a similar view of one end of the support and illustrating the manner of attachment to the frame of a door or window and also the method of hanging a valance therefrom.

Fig. 3 is a perspective view of a corner of a room and illustrating the application of the invention to windows of both the square and arched type.

Fig. 4 is a perspective view of the improved support and illustrating the manner of its application when employed to support draperies from the ceiling of a room.

Referring to the drawings, a curtain or valance support constructed in accordance with the invention is shown as comprising a flat strip 1 of aluminum or other suitable deformable material which is provided with rows of apertures 2 and 3 adjacent to the edges thereof (Fig. 1). These strips may be manufactured in prescribed stock lengths, twelve feet for example, and subsequently cut into shorter lengths to order or at the time of hanging the support.

In practice a desired length of the strip is cut from the strip of stock material and secured to the upper surface of a door or window frame 4 by nails or screws 5 inserted through the apertures 2. The strip is of such width that when thus secured in position it will extend outwardly from the frame sev-

eral inches so that when the draperies are hung therefrom they will be spaced from the window the proper distance.

A valance or drape 6 is preferably suspended from the support by means of hooks 7 which are suitably attached thereto for removable engagement with the apertures 3 provided along the outer edge of the support. This method of suspending the drape 10 from the support insures that if gathers in the drape are desired they will be maintained against displacement in a manner pleasing to the eye.

When the support is secured to a rectangular window frame the strip 1 is preferably cut to such length that when secured to the top of the frame its ends will extend outwardly therefrom an appropriate distance. These ends are then bent downwardly at 20 right angles to the intermediate portion of the strip to form depending legs 8 which are secured to the edges of the vertical sides of the frame 4 as illustrated in Fig. 2. In this construction the valance or curtain 6 is carried around the corner thus formed and the end hook 7 inserted into one of the apertures 2 in the rear edge of the support.

When the support is applied to a window having an arched frame, as illustrated at 9 30 in Fig. 3, the strip 1 is bent around the frame and secured thereto in the manner described in connection with Fig. 2. In this case the strip may be carried down on each side of the frame as far as may be desirable in order 35 to secure the drapes to the side frame of the window.

It frequently occurs that the door or window either is not provided with a frame or that it extends entirely to the ceiling and therefore to provide for such a contingency the strip 1 is bent longitudinally along a median line as indicated at 10 in Fig. 4 so as 40 to provide a support of angle-iron construction having a flange 11 for attachment to the wall or ceiling and a flange 12 extending at right angles thereto to which the drapes are attached. This type of support is of considerable utility in hanging draperies in large 45 rooms, halls, lobbies and the like and where it is desired to extend the curtains over the walls so as to give the appearance of a door or window of larger size.

It will be obvious from the foregoing that in a support of the character described there 50 is little or no waste for the reason that a number of short lengths of the strip 1 may be secured together by bolts or screws inserted through the apertures 2 and 3.

The strips may be manufactured in varying widths and gages according to the particular use to which it is to be applied and is of sufficient tensile strength to permit of its use in hanging relatively heavy draperies but 60 is sufficiently pliable to permit being bent

either laterally or longitudinally according to the type of hanging.

From the foregoing it will be apparent that a very inexpensive and practical curtain support is provided and one that may be adapted to many uses and to doors, windows, alcoves and the like of varying widths with a minimum of effort and with practically no waste.

The invention may be modified in construction and arrangement without departing from the nature of the invention as defined in the appended claims.

What is claimed is:

1. A valance hanger for use with a window having a top frame and side frames, comprising a metallic strip having an intermediate portion secured to the upper surface of said top frame and extending outwardly therefrom in the plane thereof, and depending end portions secured to the outer surfaces of said side frames and extending outwardly therefrom in the plane thereof.

2. A hanger for curtains or valances comprising a flat strip of deformable material having a series of spaced apertures along each edge thereof and bent along a longitudinal median line to provide a flange for attachment to a support and a flange extending transversely thereto for attachment to a curtain or valance.

3. A valance hanger for use with a window having a frame, comprising a strip secured to the outer surface of said frame in overhanging relation thereto and in the plane of said surface, said strip being transversely deformable to readily conform to the contour of the periphery of the portion of the frame to which it is secured and said frame cooperating with said strip to reinforce the same against further deformation under the weight of said curtain when said strip is secured thereto.

4. A reversible valance hanger, comprising a strip having a series of spaced apertures adjacent each of its longitudinal edges, either of said edges being attached to a support through its adjacent apertures, and the remaining edge overhanging the support and adapted to receive valance attaching means in its adjacent apertures to support a valance.

5. A valance hanger comprising a thin flexible strip having a series of spaced apertures adjacent each of its longest edges, one of said edges being attached to the outside of a window frame through its adjacent apertures and the remaining edge receiving valance attaching means in its adjacent apertures to support a valance, said flexible strip being bent to conform to the top portion of the window frame.

6. A valance hanger for attachment to the top of a window frame and portions of the sides adjacent to said top, comprising a bendable strip having a series of spaced aper-

tures adjacent each of its longest edges, said strip being bent to conform to the top and the said side portions of the window frame, and attached thereto for its entire length through the apertures in one of the said edges, the remaining edge projecting from said window frame and adapted to receive valance attaching means in its adjacent apertures to support a valance.

- 5 10 7. A valance hanger comprising a flexible strip conformable to the top portion of a curved window frame, said strip having spaced attachment receiving portions adjacent one of its longitudinal edges, and having spaced valance supporting portions adjacent its opposite edge, and means for securing said strip to the top portion of the window frame through said attachment receiving portions.
- 15 20 8. A valance hanger comprising a strip having a series of apertures adjacent each of its longest edges said strip being symmetrical about its longest median line, either of said edges being mountable on a support 25 through its adjacent apertures.
